UNITED STATES PATENT OFFICE.

WILLIAM THOMAS OSBORNE, OF SALEM, OHIO, ASSIGNOR TO THE GEORGE H. BOWMAN COMPANY, OF CLEVELAND, OHIO, A CORPORATION OF OHIO.

DESIGN FOR ORNAMENTATION FOR AN ARTICLE OF MANUFACTURE.

57,412.

Specification for Design.

Patented Mar. 22, 1921.

Application filed January 8, 1918. Serial No. 210,943. Term of patent 3½ years.

To all whom it may concern:

Be it known that I, WILLIAM THOMAS OSBORNE, a citizen of the United States, residing at Salem, in the county of Columbiana and State of Ohio, have invented a new, original, and ornamental Design for Ornamentation for an Article of Manufacture, of which the following is a specification, reference being had to the accompanying drawings, forming a part thereof.

Figure 1 is a perspective view of a vessel to which my design is applied; Fig. 2 is a fragmentary view on an enlarged scale of a portion of the article shown in Fig. 1.

I claim:

The ornamental design for ornamentation for an article of manufacture as shown and described.

WILLIAM THOMAS OSBORNE.
